UNITED STATES PATENT OFFICE

2,449,706

GALVANIC WATER PROCESSING
APPARATUS

Theodore C. Jones, Louisville, Ky.

Application January 10, 1945, Serial No. 572,146

3 Claims. (Cl. 204—248)

1

My invention relates to a novel apparatus for processing water by means of a galvanic pile, to precipitate mineral salts and the like therefrom, said apparatus being intended primarily for processing boiler feed water.

The principal object of the invention is to provide a simple and inexpensive apparatus which may be easily installed, will be efficient and long-lived, and will permit easy renewal of the galvanic pile whenever required.

In carrying out the above, further objects are to provide a novel galvanic pile unit for installation in the water-treating tank; and to make novel provision for yieldably holding said unit between a removable end wall of the tank and a resilient support within said tank.

With the foregoing in view, the invention resides in the novel subject matter hereinafter described and claimed, description being accomplished by reference to the accompanying drawings.

Fig. 1 is a vertical sectional view through the apparatus, the removable end wall of the tank being secured in place to secure the removable galvanic pile unit in the tank.

Figs. 2 and 3 are horizontal sectional views on lines 2—2 and 3—3 of Fig. 1.

Fig. 4 is a view similar to Fig. 1, partly in elevation, showing the relation of parts before the removable end wall of the tank is secured in place.

Fig. 5 is a side elevation of the galvanic pile unit.

A preferred construction has been illustrated and will be specifically described, with the understanding that within the scope of the invention as claimed, variations may be made.

A vertical, preferably cylindrical tank 6 is provided, said tank having a hopper-like lower end 7 which is equipped with a gate valve or the like 8 for removal of the precipitate. The upper end wall 9 of the tank 6 is removable, being preferably held in place by suitable bolts 10 against a gasket 10'. Near its upper end, the tank 6 is provided with a water inlet 11, and a water outlet 12 is provided near the lower end of said tank, for connection with the boiler. A steam manifold 13 surrounds the tank 6 near its lower end, said manifold having a steam inlet 14 and a plurality of steam discharge nozzles 15, said nozzles extending through the tank wall. Steam from the boiler injected into the water being treated in the tank 6, through the nozzles 15, highly heats said water to insure thorough precipitation of mineral salts and the like therefrom. To take

2

care of any steam which does not condense in passing through the water in the tank 6, an outlet 16 may be provided at the tank top, for connection with a pressure blow-off valve or the like (not shown).

Near its lower end, the tank 6 is provided with an internal upwardly facing shoulder 17. When the hopper-like lower end 7 is formed separately from the major portion of the tank, and bolted to the latter as seen at 18, said lower end 7 may be of sufficiently small internal diameter at its upper end to permit it to form the shoulder 17. A resilient support 19 for a galvanic pile unit 20, rests upon the shoulder 17, said support preferably comprising a central hub 21 and radial arms 22 which decline from said hub. These arms and the hub are of appropriate material, such as a springy metal and in the present showing are formed integrally with each other, the outer ends of said arms resting upon the shoulder 17. The hub 21 is formed with a central opening 23 which receives the lower end of a vertical rod 24 forming part of the galvanic pile unit 20. There is a nut 25 threaded on the rod 24 and resting upon the hub 21, and said rod carries another nut 26 near its upper end. This upper end of the rod abuts the removable cover 9, which cover is preferably formed with a shallow socket 9' to receive and center said rod end. Two insulating washers 27 and 28 abut the inner sides of the nuts 25 and 26 respectively and also abut the ends of an insulating sleeve 29 which surrounds the rod 24. The positive and negative electrodes 30 and 31 of the galvanic pile 20 are formed with central openings 32 through which the sleeve 29 passes, said electrodes being held in tight contact with each other by the rod, nuts and washers. The positive electrodes 30 are of frusto-conical form, with their peripheries steeply inclined to effectively shed any precipitate settling thereon, and the negative electrodes 31 are cylindrical, and said positive electrodes preferably have shallow recesses 33 receiving the ends of said negative electrodes. The diameter of each positive electrode 30, at its upper end, may be only slightly greater than the diameter of the negative electrodes 31, as shown.

The length of the galvanic pile unit 20 is such that when it is supported upon the resilient support 19, the cover 9 will contact with its upper end before said cover is drawn home by tightening of the bolts 10. Thus during tightening of these bolts and drawing of the cover 9 into place, the resilient support 19 is compressed as will be seen by comparing Figs. 1 and 4. The

resilient support 19 is thus held under tension to solidly hold the entire unit 20 clamped in place between said support and the cover 9, and this solid holding of said unit will not vary with expansion and contraction of the apparatus.

When replacing of electrodes is required, the cover 9 is removed and the entire unit 20 easily withdrawn from the tank 6. This withdrawn unit may now be easily reconditioned for reinsertion in the tank, or an entirely new unit may be substituted.

Obviously the positive and negative electrodes may be formed from any appropriate materials, copper being one example for the positive electrodes 20 and zinc being one example for the negative electrodes 31. It is also obvious that instead of injecting steam into the tank to heat the water, the heating may be done by arranging a steam coil in water in the tank.

From the foregoing, taken in connection with the accompanying drawings, it will be seen that novel and advantageous provision has been made for attaining the desired ends, and while preferences have been disclosed, attention is again invited to the possibility of making variations within the scope of the invention as claimed.

I claim:

1. In a water processing apparatus, a vertically elongated galvanic pile comprising vertically spaced frusto-conical positive electrodes entirely free from contact with each other and all having their smaller ends disposed upwardly, the peripheries of all of said positive electrodes being steeply inclined to shed any precipitate settling thereon, cylindrical negative electrodes between said positive electrodes and of no greater diameter than the smaller upper ends of said positive electrodes, said positive and negative electrodes being axially aligned vertically, and means extending through said positive and negative electrodes and

holding said positive electrodes in contact with said negative electrodes.

2. A structure as specified in claim 1; said positive electrodes having shallow sockets receiving the ends of said negative electrodes.

3. A water processing apparatus comprising a vertically elongated tank having a removable upper end wall formed with a central downwardly open socket, said tank having an internal upwardly facing annular shoulder near its lower end, a support in said tank comprising a central hub and resilient arms radiating from said hub, said arms resting at their outer ends on said shoulder, said hub having a central opening, and a vertically elongated galvanic pile unit in said tank and resting on said hub, said unit having a central downward projection removably received in said opening of said hub, and a central upward projection removably received in said socket of said upper end wall, said resilient arms being under such tension as to press said unit upwardly against said upper end wall.
